UNITED STATES PATENT OFFICE.

JAMES EDWARD GARVIN, OF ALBANY, NEW YORK.

ANCHOR.

1,249,062.

Specification of Letters Patent. Patented Dec. 4, 1917.

Application filed February 17, 1916. Serial No. 78,888.

To all whom it may concern:

Be it known that I, JAMES E. GARVIN, a citizen of the United States, and a resident of Albany, in the county of Albany and 5 State of New York, have invented a new and Improved Anchor, of which the following is a full, clear, and exact description.

My invention relates to means for anchoring the guy rods of telephone poles or the 10 like, and it has for an object to provide an anchor that may be employed as a substitute for the wood and metal anchors now generally used.

A further object of the invention is to 15 provide an anchor that may be formed of burned clay and be given a design that will afford a large working surface or area in contact with the sides of the anchor hole and still keep well within the cost of other forms 20 of anchors.

Another object of the invention is to provide an anchor element that may be utilized for the effective anchoring of a rod where the hole in the earth is cylindrical or where 25 the nature of the soil requires the making of an irregular hole to receive the anchor means.

The invention also has for an object to 30 provide an anchor of a character whereby to effect the anchoring of a rod with convenience and despatch and at a cost below that incident to the use of wood or metal anchors.

The invention will be particularly explained in the specific description following.

Reference is to be had to the accompanying drawings forming part of this specification in which similar reference characters indicate corresponding parts in all the views.

40 Figure 1 is a perspective view of an anchoring element formed in accordance with my invention;

Fig. 2 is a side elevation of the said element in use on a rod;

45 Fig. 3 is a view similar to Fig. 2 showing the employment of two of the elements shown in Fig. 1;

Fig. 4 is a view similar to Fig. 3 showing another manner of employing two of the 50 anchoring elements;

Fig. 5 is a view similar to Figs. 2 to 4, but showing a modified form of the anchoring element.

In carrying out my invention in the form 55 shown in Figs. 1 and 2, I produce an anchor-

ing element 10, in the form of a plug adapted to be inserted in a hole in the ground. In the preferred form this element is formed of earthenware, that is, burned clay, which may advantageously be vitrified, or hard 60 burned terra-cotta.

The element 10 is cut away at one side to present a lateral plane or surface oblique to the axis of the plug. The base 12 of the element 10 is cylindrical and the oblique 65 plane 11 extends from the outer end 13 to the base 12, that is to say, short of the inner end of the plug.

Also, it is to be observed the said plane presents for its major portion a broad flat 70 surface extending continuously and unbroken from side to side of the anchoring element to afford an ample wedging surface. The cylindrical base serves to center the plug in the hole and with the relatively 75 large area at the opposite side bearing against the wall of the hole, the individual element resists a tendency to be tilted.

A longitudinal through-bore 14 is produced in the plug at one side of the center, 80 that is to say, adjacent to one side of the plug, and thus eccentrically positioned for receiving a rod A to be anchored, said rod being of known form and adapted to receive a nut B on the end thereof after the placing 85 of an element, or elements, 10, as herein-after explained. The upper terminal of the oblique face 11 is preferably inward from the adjacent side of the plug so that the bore 14 extends through the flat outer end 90 13. In the preferred form, the plug 10 has a longitudinal groove 15 extending through the cylindrical base 12 from the lower end of the plug to the lower end of the oblique plane 11 and the through-bore 14 is at the 95 opposite side, that is, diametrically in line transversely with the said groove 15. The eccentric position of the rod A develops in the latter the maximum resistance when subjected to strain.

100 In installing the element 10, the same may be used singly as in Fig. 2. As usual an oblique hole is formed in the ground and the said element is passed on to the rod A and held thereon by the nut B. The space 105 formed between the oblique plane 11 and the opposite side wall of the hole may be filled with broken stone as indicated at 16, Fig. 2, and the stone firmly tamped into place. This way of employing the invention 110

is particularly adapted for anchoring the rod in holes where the soil does not permit of the hole being bored with an earth auger but necessitates the forming of a hole with 5 irregular walls.

It is to be observed that the lateral surface of the plug other than that of the oblique plane 11, forms part of the same cylindrical surface with the base 12, whereby a broad 10 contact surface is presented to the walls of the hole, and this formation, employed with the tamping of the broken stone into the space between the oblique surface and the opposed wall of the hole, serves to firmly 15 hold the anchor in position.

Fig. 3 illustrates the use of two of the elements 10 when a regular hole can be bored with an earth auger. In employing the two anchoring elements as in Fig. 3, the 20 one element is secured the same as shown in Fig. 2, and inserted in the hole to the bottom. A second element is then placed in position on the rod A, the latter being received in the longitudinal groove 15, whereby the said second element will ride on the rod, the groove 15 serving to guide the said element to position and afford clearance for the movement of the element in taking a 25 seat on the first element with the opposed 30 oblique planes 11 in contact. The hole is then back filled with earth as indicated at 16^a.

In Fig. 4, still another manner of employing the two elements 10 is shown. In this 35 figure it will be seen that two of the elements 10 are employed in corresponding positions instead of being reversed as in Fig. 3. In installing the anchor the two elements are slipped onto the rod A and said rod inserted 40 in the hole, the lower element 10 being lowered to the bottom of the hole and a filling 16^b of stone tamped in position, while the second element will be swung around on the rod and maintained at the top of the ground 45 until the first element is tamped in. The second element is then placed in position and a second stone filling 16^b then applied.

In Fig. 5 a modified form of plug 10^a is shown, which has a cylindrical base 12^a and 50 a longitudinal bore 14^a extending axially in the said plug to receive the anchor rod A. With this form of plug, oblique faces 11^a are formed at opposite sides of the axial bore 14^a, said oblique surfaces advantageously being somewhat curved. Desirably 55 the outer end 13^a of the plug 10^a is flat at the center between the oblique faces 11^a, that is to say, the said oblique faces at their upper ends do not cut into the bore 14^a. With 60 this form of the invention, broken stone 16^c is tamped in the hole above the plug and in the spaces between the oblique faces 11^a and the walls of the hole.

In all forms the anchoring element, it 65 will be observed, constitutes a wedge coact-

ing with a similar element as in Fig. 3 or with the filling of earth or stone as in the other figures.

Having thus described my invention I claim as new and desire to secure by Letters 70 Patent:

1. A rod anchoring element in the form of an elongated plug having a longitudinal bore for receiving a rod to be anchored, and adapted to be inserted in a hole in the 75 ground, the base of the said plug being cylindrical, and said plug presenting a side surface extending to the upper end thereof and forming part of the same cylindrical surface with the said base, the said plug furthermore, at a side thereof, presenting a plane oblique to the axis of the plug. 80

2. A rod anchoring element in the form of an elongated plug having a longitudinal bore for receiving a rod to be anchored, and 85 adapted to be inserted in a hole in the ground, the base of the said plug being cylindrical, and said plug presenting a side surface extending to the upper end thereof and forming part of the same cylindrical 90 surface with the said base, the said plug furthermore, at a side thereof, presenting a plane oblique to the axis of the plug, said oblique plane extending from the upper end of the plug and terminating short of the 95 lower end.

3. A rod anchoring element in the form of a plug adapted to be inserted in a hole in the ground, a side of said element being cut away presenting an oblique plane at one side 100 extending from the cylindrical base to the upper end, there being a longitudinal through-bore in said element at one side of the center, between the said oblique plane and the opposite side surface, said opposite 105 side surface and the said base forming part of the same cylindrical surface, and there being a longitudinal slot in the base extending from the lower end to said oblique plane and diametrically in line with the said bore. 110

4. A rod anchoring element in the form of an elongated plug having a longitudinal bore for receiving a rod to be anchored, and adapted to be inserted in a hole in the 115 ground, the base of the said plug being cylindrical, and said plug presenting a side surface extending to the upper end thereof and forming part of the same cylindrical surface with the said base, the said plug furthermore, at a side thereof, presenting a 120 plane oblique to the axis of the plug, said oblique plane extending from the upper end of the plug and terminating short of the lower end, there being a longitudinal slot in the base extending from said oblique 125 plane to the lower end of the plug.

5. A rod anchoring device in the form of a wedge, and having a longitudinal through-bore to receive a rod to be anchored, said bore ranging substantially parallel with the 130

axis of the wedge adjacent to one side thereof between said side and the center so that the anchored rod will cause the anchoring element to bear with increased pressure 5 against the opposed wall of the hole in which the rod is to be anchored.

6. A rod anchoring device including a plug adapted to enter the hole in which the rod is to be anchored, and having means to 10 receive the rod, said plug having a wedge formation at the upper portion and a non-wedging base portion below the wedge formation, presenting an external surface at all sides parallel with the axis of the plug, the said wedge portion and the said base portion being co-terminous a distance above 15 the bottom surface of the plug.

7. A rod anchoring element having a passage therethrough to slidably receive the rod to be anchored, said element being cut away 20 at one side presenting a plane inclined to the axis of the element, said plane extending from the upper end and terminating short of the base end, and said element presenting a lateral surface at the opposite side 25 substantially parallel with the axis.

In testimony whereof I have signed my name to this specification in the presence of two subscribing witnesses.

JAMES EDWARD GARVIN.
